DESIGN FOR A TOY FORTRESS

Ralph M. Anthony, Detroit, Mich.

Application April 23, 1945, Serial No. 119,150

Term of patent 7 years

(Cl. D34—15)

To all whom it may concern:

Be it known that I, Ralph M. Anthony, a citizen of the United States, residing at Detroit, in the county of Wayne and State of Michigan, have invented, a new, original, and ornamental Design for a Toy Fortress, of which the following is a specification, reference being had to the accompanying drawing, forming part thereof, wherein:

Fig. 1 is a top plan view of a toy fortress showing my new design.

Fig. 2 is a front view of the fortress, in partial section on the line 2—2 of Fig. 1.

Fig. 3 is a side elevational view, in partial section on the line 3—3 of Fig. 1.

Fig. 4 is a sectional view taken on the line 4—4 of Fig. 1.

I claim:

The ornamental design for a toy fortress, as shown.

RALPH M. ANTHONY.
